BY J. H. Gibbs

ATTORNEY.

UNITED STATES PATENT OFFICE.

JOHN W. STEINMEYER, OF EAST ORANGE, NEW JERSEY, ASSIGNOR TO AMERICAN CAR AND FOUNDRY COMPANY, OF NEW YORK, N. Y., A CORPORATION OF NEW JERSEY.

UNCOUPLING DEVICE.

1,354,923.

Specification of Letters Patent.

Patented Oct. 5, 1920.

Application filed January 15, 1920. Serial No. 351,715.

To all whom it may concern:

Be it known that I, JOHN W. STEINMEYER, residing at East Orange, county of Essex, State of New Jersey, and being a citizen of the United States, have invented certain new and useful Improvements in Uncoupling Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Figure 1 is a front elevational view of a portion of a car end showing my invention in position thereon;

Fig. 2 is a plan view of the same;

25 Fig. 3 is an enlarged fragmentary view of the pivoting mechanism looking in the direction indicated by arrow 3 in Fig. 2; and

Fig. 4 is a plan view of the same looking in the direction indicated by arrow 4 in Fig. 3.

30 The object of my invention is to provide an uncoupling mechanism of the two-lever type in which the levers are held in assembled position on the car by means of an interlocking fulcrum bracket on one of said levers and a supporting fulcrum on the car.

Other objects and advantages will appear in connection with the drawings in which 10 designates an end of a car equipped with my invention; 11, the car coupler provided

40 with the usual locking-pin 12; 13 represents the operating lever of the uncoupling mechanism, and 14 the pin lifting lever. Operating lever 13 is secured to an extension forming a fulcrum bracket 15 adapted to receive 45 supporting fulcrum 16 on the car.

The fulcrum bracket 15 is formed with a lever attaching flange 17 terminating in a sleeve 18 for receiving the fulcrum 16, and a superposed stud 19 rising from a base-plate

50 20. An overhanging ledge portion 21 is projected from upper side of stud for engaging pin lifting lever 14. In the embodiment shown the ledge 21 is extended downwardly to the base plate 20, to give the bracket 55 greater stability during the pin lifting op-

eration. The overhanging ledge portion 21 is spaced from stud 19 to provide a passageway 22 for the open hook 23 of the pin lever 14 as shown in Figs. 3 and 4.

The pin lifting lever 14 is flexibly connected with operating lever 13 through the medium of the open hook 23 moving between ledge 21 and base plate 20, and embracing stud 19 about which the pin lever pivots in response to the longitudinal movements of 60 the coupler. Separation of pin lever and stud 19 is prevented by the overhanging ledge 21 which engages the upper side of the hook 23 during the pin lifting operation. This ledge and base plate 20 of the fulcrum 70 bracket provide the means for the transmission of power from the operating lever 13 to the coupler pin 12 through pin lever 14, for when the operating lever is drawn downwardly as shown by broken lines in Fig. 1, 75 the under side of the ledge bears upon the upper edge of the hook 23 while the underside thereof rests upon base plate 20 above the fulcrum 16.

It will be noted that the pivot stud 19 is 80 positioned on operating lever 13 some distance from fulcrum 16 to provide sufficient overlap of levers 13 and 14 for transmitting power from one to the other without unduly straining the connections. Base plate 85 20 is provided with an upstanding abutment 24 above the fulcrum 16 designed to engage said lever to check abnormal lateral movement thereof, while stop lug 25 on fulcrum 16 is in position to engage the underside of 90 base plate 20 as shown in Fig. 3 to limit downward sweep of operating lever 13 after raising coupler pin 12 to release position indicated by broken lines in Fig. 1.

The mechanism is held to the car by a 95 bolt 26 or the like, extending through sleeve 18 of the fulcrum bracket, washer 27, fulcrum 16, and a fulcrum supporting bracket 28 secured to the car. With the mechanism held in position by the bolt 26 as indicated, the parts thereof are interlocked but with such flexibility of connection between said parts as to permit necessary lateral and longitudinal play of the coupler.

It will be noted that the hook 23 of pin 105 lever 14 is adapted to be engaged by ledge 21 of the fulcrum bracket and base plate 20 at points substantially in line with pivot stud 19 to prevent rotation of the lever about its longitudinal axis and transmit a balanced 110

pin lifting force to the pin connection portion 14^a of the lever. This is accomplished by deflecting the hook 23 from the body of the lever to overcome eccentricity in the application of the pin lifting force as above described.

With the mechanism held in position by a single securing element the difficulty heretofore experienced in disassambling worn or damaged parts is largely overcome. The parts are connected by interlocking, and no special tools are required to assemble them.

What I claim is:

1. In an uncoupling device comprising 15 operating and pin-lifting levers, a supporting fulcrum, and a fulcrum bracket adapted to receive said fulcrum and flexibly connect said levers so that said levers use said fulcrum in common.
2. In an uncoupling device comprising 20 operating and pin-lifting levers, a supporting fulcrum, and a fulcrum bracket carrying one of said levers and adapted to receive said fulcrum, said bracket including 25 means for connecting said levers so that said levers use said fulcrum in common.
3. In an uncoupling device comprising 30 operating and pin-lifting levers, a supporting fulcrum, and a fulcrum bracket adapted to receive said fulcrum and connect said levers so that said levers use said fulcrum in common.
4. In an uncoupling mechanism comprising 35 operating and pin-lifting levers, a supporting fulcrum, a fulcrum bracket carrying one of said levers and sleeved to receive said fulcrum, said bracket being adapted to provide means for flexibly engaging the other of said levers so that said levers use 40 said fulcrum in common.
5. In an uncoupling mechanism comprising 45 a plurality of levers, a fulcrum common to said levers, a fulcrum bracket on one of said levers sleeved to receive said fulcrum and providing a connection for the other of said levers, said levers overlapping between said connection and the fulcrum.
6. In an uncoupling device comprising 50 operating and pin-lifting levers in overlapping relation, a fulcrum common to said levers, said operating lever terminating in a fulcrum bracket sleeved to receive said fulcrum and provided with a superposed pivot, said pin-lifting lever being adapted for interlocking engagement with said pivot.
7. In an uncoupling device comprising 55 operating and pin-lifting levers, a supporting fulcrum, said operating lever terminating in a fulcrum bracket sleeved to receive said fulcrum and provided with a superposed pivot, and an open hook on the pin-lifting lever having interlocking engagement with said pivot.
8. In an uncoupling device comprising 60 operating and pin-lifting levers, a support-

ing fulcrum, said operating lever terminating in a fulcrum bracket sleeved to receive said fulcrum and provided with a base plate and a superposed pivot, said pin-lifting lever being supported upon said base plate 70 and adapted for interlocking engagement with said pivot.

9. In an uncoupling device including an operating lever, a supporting fulcrum, said operating lever terminating in a fulcrum 75 bracket sleeved to receive said fulcrum and provided with a base plate, and a stop lug on the supporting fulcrum to limit downward movement of said lever upon contact with said base plate.

10. In an uncoupling mechanism including an operating lever, a supporting fulcrum, said operating lever terminating in a fulcrum bracket sleeved to receive said fulcrum and provided with a base plate and 85 superposed pivot, a ledge projecting from the upper side of said pivot, and a pin-lifting lever positioned between said ledge and base plate and engaging said pivot.

11. In an uncoupling device comprising 90 a supporting fulcrum, a fulcrum bracket mounted on said fulcrum, an operating lever for said bracket and a pin-lifting lever pivotally connected to said bracket so as to fulcrum on said supporting fulcrum.

12. In an uncoupling device comprising a supporting fulcrum, a fulcrum bracket on said fulcrum, operating means for said bracket, a pin projecting from said bracket and a pin-lifting lever pivotally mounted 100 on said pin and extending over said fulcrum.

13. In an uncoupling device comprising a supporting fulcrum, a fulcrum bracket mounted on said fulcrum, operating means 105 for said bracket and a pin-lifting lever pivotally mounted on said bracket and extending over said fulcrum.

14. In an uncoupling device comprising a plurality of levers, a fulcrum common to 110 said levers and a fulcrum bracket on one of said levers sleeved to receive said fulcrum and providing a flexible connection for the other of said levers, said levers overlapping between said connection and said fulcrum.

15. In an uncoupling device comprising operating and pin-lifting levers in overlapping relation, a supporting fulcrum, and a fulcrum bracket sleeved to receive said 120 fulcrum and provided with a superposed pivot, and an open hook on the pin-lifting lever having flexible interlocking engagement with said pivot.

16. In an uncoupling device comprising 125 operating and pin-lifting levers, a supporting fulcrum, said operating lever terminating in a fulcrum bracket sleeved to receive said fulcrum and provided with a superposed pivot and a ledge projecting from the 130

upper side of said pivot, the pin-lifting lever being adapted to engage the underside of said ledge.

17. In an uncoupling device, an operating lever, a pin-lifting lever, a fulcrum and a fulcrum bracket joining said levers so that said levers use said fulcrum in common.

In witness whereof I have hereunto set my hand in the presence of two witnesses.

JOHN W. STEINMEYER.

Witnesses:

OSCAR HOCHBERG,
R. W. SMITH.
